H. RESCH

TYPEWRITING MACHINE

Filed Oct. 15, 1924.

UNITED STATES PATENT OFFICE.

HENRY RESCH, OF BAYONNE, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed October 15, 1924. Serial No. 743,668.

This invention relates to means for gag-
ing work-sheets or the like, in a typewriting
machine, especially one having a platen-
sweep or work-sheet inserter, whereby the
5 platen is rapidly swept through a mechani-
cally-limited stroke to carry the gaged sheet
to the printing point, and embodies features
of improvement on the gage disclosed in
the application of Harry H. Vickers, Serial
10 No. 543,971, filed March 15, 1922. A work-
sheet inserter of the type suitable for use
with the present invention, is disclosed in
patent to Kurowski, 1,499,936, of July 1,
1924, or in the patent to Henning, 1,095,573,
15 of May 5, 1914.

One of the features of the present invention
is the provision of a stationary gage
positioned adjacent the rear of the platen for
facilitating the rapid introduction, gaging
20 and squaring of a sheet prior to running
the same around with the platen to exact
typing position.

Another feature is the provision of means
for facilitating the easy manipulation of
25 the sheet to adjust the same to the gage.

A further feature of the invention relates
to novel and simplified means for side gag-
ing the sheets.

Other features and advantages will here-
30 inafter appear.

In the accompanying drawings,

Figure 1 is a front elevation of the upper
portion of a typewriting machine equipped
35 with a work-sheet inserter, and showing the
present invention in position.

Figure 2 is a transverse section, in the
direction of the arrows, on the line 2—2 of
Figure 1.

Figure 3 is a similar view on the line 3—3
40 of Figure 1.

A rotary platen 10 is fixed to a platen-
shaft 11 journaled in the end walls 12 and
13 of a platen-frame 14. The platen may
45 be rotated in the usual manner by hand-
wheels or knobs 15 and 16 fixed to the ends
of the platen-shaft 11. An introductory
paper-table 17 occupies the usual position at
the rear of the platen-frame 14, and it will
50 be noted that said table extends considerably
above the plane of the platen-frame. A
work-sheet S may be fed over the introductory
paper-table, thence between the platen
and feed-rolls 18 and 19, and upwardly to
55 the printing point of the type 20. It is
desirable in using a short work-sheet on

which typing is done only on a single line, to
run the sheet rapidly to the exact printing
point of the platen after it has been properly
gaged; and for this purpose a rapid sheet-
inserter 21, including a handle H, having 60
a mechanically-measured stroke, is used.
The sheet-inserter 21 may be of the stand-
ard construction, such as illustrated in the
Kurowski and Henning patents above re-
ferred to, or any other similar device to ac-
complish the purpose mentioned. For
65 mounting my improved gage in proper pos-
ition with relation to the platen and to the
introductory paper-table, there is provided
a rod 22 which extends lengthwise of the
70 machine, adjacent the rear of the platen, the
ends of the rod being suitably secured in the
ends 12 and 13 of the platen-frame. A pair
of riders or slides 23, each of which com-
75 prises a substantially yoke-shaped member
24 and a hub portion 25, are suitably per-
forated at 24' and 25' to be received upon
the rod 22. The rod 22 has a spline 22', and
a detent 23' is pressed by a spring 26 into
80 engagement with the spline to hold the slides
23 in slidable relation upon the rod. Set
screws 26' are threaded through the hubs
25 to adjustably secure the riders upon the
shaft. Arms 27 form a portion of the yoke-
85 members 24, and are directed rearwardly
of the machine and toward the introductory
paper-table 17. The ends of the arms are
bent at right angles to form securing feet
28. It has been found that standard paper-
90 fingers of the type used around the platen
may be conveniently altered to suit the pur-
poses of the slides 23 as described. A gage-
member or secondary paper-table 29, which
95 may comprise a piece of sheet material
stamped and bent to form, is provided with
depressions 30 and slots 31, the depressions
being properly spaced apart to be received
upon the feet 28. A screw 32 passes through
100 each of the slots 31 of the depressions 30,
and into a screw-threaded perforation of
each of the feet 28, so that the gage 29 is ad-
justable upon the slides 23. The upper por-
tion of the gage-member is bent outwardly
105 at right angles toward the introductory pa-
per-table 17 to form a ledge or stop 33
against which a sheet introduced between
the paper-table and the gage-member may be
properly gaged prior to running the sheet
110 around the platen by operation of the sheet-
inserter 21. For facilitating the easy ma-

nipulation of a sheet while being brought to position against the ledge or stop 33, the upper edge of the gage-member 29 is cut away as at 34, at a point intermediate its ends so as to provide clearance for the fingers of the operator. The usual paper-fingers 35 and 36 are provided for guiding and holding the sheet upon the platen while being run to the printing point, and a side gage 37 is secured upon the upper portion of the paper-finger 36 by means of screws 38, and is effective to properly position the work-sheet laterally while the same is being brought to position against the stop 33. It will be noted that the introductory paper-table extends considerably above the ledge or stop 33 of the gage-member 29, this being advantageous as it aids materially in the handling of a sheet while being introduced into the machine and brought to position against the gaging stop 33. The gage-member 29 forms with the paper-table 17 a work-inserting throat and provides a finger-space for easy manipulation of the work-piece in positioning the same against the stop 33.

In operation the feed-rolls 18 and 19 are released, and the handle H of the inserter 21 is thrown to the position indicated in Figure 2, after which the sheet S is led down between the gage-member 29 and the introductory paper-table 17, and properly adjusted so as to bring the upper edge thereof against the stop 33, and, due to the fact that the paper-table extends considerably above the gage 29, the ease with which the sheets may be handled is greatly facilitated. The feed-rolls 18 and 19 are then applied to grip the sheet against the platen, and the handle H is thrown rearwardly of the machine to the position illustrated in Figure 3. During this time the sheet has been carried around with the platen and properly positioned so as to bring the desired printing line thereof exactly opposite the type 20, which may then be operated to type upon the sheet. After having completed the typing operation the feed-rolls 18 and 19 may be released, and the sheet withdrawn upwardly from the front of the machine, and a new sheet introduced and handled in the same manner as already described. It will be readily seen from the position of the gage, and, due to the fact that the paper is introduced against the rear surface thereof, and then brought up against the gaging stop, that the ease and rapidity with which sheets may be gaged and introduced into the machine is greatly facilitated. It is also apparent that a plurality of work-sheets with interleaved transfer-sheets may be gaged and run into the machine in the same manner as a single sheet.

Variations may be resorted to within the scope of the invention, and portions of the improvements may be used without others.

Having thus described my invention, I claim:

1. In a typewriting machine, in combination, a revoluble platen, feed-rolls, an introductory paper-table, a secondary paper-table adjacent the rear of the platen and facing said introductory paper-table, the tables thereby providing a work-introducing throat for a work-piece thrust downwardly therein to a position between the platen and the feed-rolls, a gage carried by said secondary table and against which the trailing edge of said work-piece is brought to a gaged position within said throat, and a platen-sweep for turning said platen through a mechanically-measured stroke, whereby to carry the gaged work-piece a predetermined distance to exact typing position. 70 75

2. In a typewriting machine, in combination, a revoluble platen, feed-rolls therefor, an introductory paper-table, a secondary paper-table adjacent the rear of the platen and including a work-engaging face disposed opposite said introductory paper-table, the tables thereby providing a work-introducing throat for guiding a work-piece thrust downwardly therein to a position between the feed-rolls and the platen, a gage adjacent the upper edge of said secondary table for gaging the trailing edge of said work-piece, said secondary table having the upper edge thereof cut away to provide clearance for easy manipulation of the work-piece in bringing the same to position against the gage, and a platen-sweep for carrying the gaged work-piece to exact typing position 90 95 100 at the conclusion of a platen-sweeping operation.

3. In a typewriting machine, in combination, a revoluble platen, feed-rolls, an introductory paper-table, a plate mounted at the rear of the platen and facing the introductory paper-table, said plate and the table forming a work-introducing throat into which a work-piece is thrust downward to a position between the feed-rolls and the platen, the upper edge of said plate being directed toward said paper-table, whereby to provide a gage against which the trailing edge of said work-piece is positioned, while the leading edge of the work-piece is between the feed-rolls and the platen, a side gage associated with said plate for side-gaging the work-piece, the side gage forming an end wall of said throat and thus confining the work-piece therewithin, and a platen-sweep for turning the platen through a mechanically-measured stroke, whereby the gaged work-piece is carried a measured distance to exact typing position at the conclusion of such stroke. 105 110 115 120 125

4. In a typewriting machine, in combination, a platen-frame, a revoluble platen, an introductory paper-table, a rod supported by the platen-frame and disposed adjacent the 130

upper portion of the rear of the platen, slides adjustably secured upon said rod, a gage-plate carried upon said slides and disposed adjacent the rear of the platen, the 5 upper edge of said plate being bent rearwardly at right angles to provide a stop, said plate providing a table against which a work-sheet may be held while gaging the edge thereof against the stop, and means for 10 turning said platen through a mechanically-limited angle to carry the gaged sheet to the printing line.

5. In a typewriting machine, in combination, a platen-frame, a revolute platen 15 mounted therein, an introductory paper-table, a rod extending parallel with the platen and supported by said platen-frame, adjustable slides mounted upon said rod, a gage-plate adjustably secured upon said 20 slides, a rearwardly-directed ledge adjacent the upper extremity of said gage-plate against which the edge of a work-sheet may be gaged to properly position the same for introduction around the platen, and means 25 for turning said platen through a mechanically-limited angle to carry the gaged sheet to the printing line.

6. In a typewriting machine, in combination, a platen-frame, a revolute platen 30 mounted therein, an introductory paper-table, a rod supported in said platen-frame and having a key-way therein, a pair of slides mounted upon said rod, spring-pressed detents for holding the slides in position upon 35 the rod, means for securing said slides in adjusted position upon said rod, a sheet-positioning plate vertically adjustable upon said slides and having the upper edge thereof turned rearwardly at right angles, so as to 40 provide a ledge against which the edge of a sheet introduced between said plate and paper-table may be gaged, and means for turning said platen through a mechanically-limited stroke so as to run the gaged sheet 45 to the printing point.

7. In a typewriting machine, in combination, a platen-frame, a revolute platen mounted therein, an introductory paper-table, a rod extending parallel with the 50 platen and supported by said platen-frame, a gage slideable upon the rod and vertically adjustable with relation to the platen, a rearwardly-disposed stop carried by said

gage for end gaging a work-sheet, sheet-guiding means supported upon the rod, a 55 side gage fixed to one of said sheet-guiding means for side gaging said sheet, and means for turning the platen through a mechanically-limited stroke to carry the gaged sheet 60 to the printing point.

8. In a typewriting machine, in combination, a platen-frame, a revolute platen therein, a rod extending parallel with the platen and supported in the platen-frame, a pair of slides adjustably secured upon the 65 rod, each of said slides including securing feet, a gage-member comprising a plate formed with depressed portions and having vertical slots therein, said depressed portions received upon said feet, screws passing through said slots and into the feet 70 for securing said gage-member in sliding relation thereupon, the upper portion of said plate being bent rearwardly at right angles to form a stop against which the 75 edge of a work-sheet is gaged, and means for turning the platen through a mechanically-limited stroke to run the gaged sheet from said stop to the printing point.

9. In a typewriting machine, in combination, a platen-frame, a revolute platen mounted therein, means for guiding a sheet around the platen, a rod extending adjacent the rear of the platen and secured to the sides of the platen-frame, a pair of supporting arms slideable upon said rod, means for securing said arms in position thereon, the free ends of said arms being turned at right angles to provide feet, a gage-plate having portions thereof pressed outwardly to 90 form depressions on the rear side of the plate, said depressed portions of the plate having slots, screws passing through the slots and into the feet so as to secure the gage-plate upon the arms, said depressions 95 being of a depth to dispose the surface of said plate above the heads of the screws, the upper portion of said gage-plate being cut away to provide clearance for easy handling of a work-sheet, a pair of stops 100 formed upon the upper rear edge of said plate against which the sheet is gaged, and means for turning the platen through a mechanically-limited stroke to run the gaged sheet to the printing line.

HENRY RESCH.
